US00D967859S

(12) **United States Design Patent** (10) **Patent No.:** **US D967,859 S**
(45) **Date of Patent:** **** Oct. 25, 2022**

(54) **MANIFOLD**

(71) Applicant: **Holley Performance Products, Inc.**,
Bowling Green, KY (US)

(72) Inventors: **Colin R. Alexander**, Bowling Green,
KY (US); **James D. Dralle**, Bowling
Green, KY (US)

(73) Assignee: **Holley Performance Products, Inc.**,
Bowling Green, KY (US)

(**) Term: **15 Years**

(21) Appl. No.: **29/755,371**

(22) Filed: **Oct. 20, 2020**

(51) LOC (13) Cl. **15-01**

(52) U.S. Cl.

USPC **D15/5**

(58) **Field of Classification Search**

USPC D15/1, 2, 3, 4, 5, 6
CPC F02M 35/104; F02M 35/108; F02M
35/1085; F02M 35/116

See application file for complete search history.

(57) **CLAIM**

The ornamental design for a manifold, as shown and described.

DESCRIPTION

FIG. 1 is an upper perspective view of a manifold showing our new design;

FIG. 2 is a lower perspective view of the design of FIG. 1;

FIG. 3 is a top view of the design of FIG. 1;

FIG. 4 is a bottom view of the design of FIG. 1;

FIG. 5 is a first side view of the design of FIG. 1;

FIG. 6 is a second side view of the design of FIG. 1;

FIG. 7 is a front view of the design of FIG. 1; and,

FIG. 8 is a rear view of the design of FIG. 1.

In the drawings, the broken lines depict unclaimed portions of the manifold only and form no part of the claimed design.

1 Claim, 8 Drawing Sheets
